UNITED STATES PATENT OFFICE.

HARRISON W. FURBER, OF BOSTON, MASSACHUSETTS.

BOOT OR SHOE.

SPECIFICATION forming part of Letters Patent No. 380,715, dated April 10, 1883.

Application filed January 17, 1888. Serial No. 261,011. (No model.)

To all whom it may concern:

Be it known that I, HARRISON W. FURBER, of Boston, county of Suffolk, State of Massachusetts, have invented an Improvement in 5 Boots or Shoes, of which the following description, in connection with the accompanying drawings, is a specification, like letters on the drawings representing like parts.

This invention has for its object the production of a boot or shoe having provision for elasticity, whereby the top of the boot or shoe may be adjusted to fit the leg of the wearer above the ankle.

In my invention the quarter of the boot or shoe has for a part of its length the usual heel-seam, and above the said seam the inturned edges of the quarter have stitched to them the edges of a strip of elastic fabric or goring, and the lining of the boot or shoe in the line of the 15 heel-seam and the center of the elastic gusset has its edges turned and stitched back after the lining is put together, so that when the seam in the lining is cut to permit greater expansion of the gore the edges left after severing the stitches will be finished edges. When 20 the shoe is finished, the lining is of such size with relation to the upper that usual strains on the lining will stretch the gore but little; but in case the shoe is too snug then the seam 25 in the lining opposite the gore is ripped, giving the gore freedom to expand. I have applied a protecting-strip between the gore and the inturned edges of the quarter above the heel-seam, and have provided the heel-seam at 30 its top near the lower end of the gore with a stay.

Figure 1 in side elevation represents a shoe embodying my invention; Fig. 2, a rear elevation; Fig. 3, a partial section in the line x , 35 and Fig. 4 a modification.

The shoe herein shown consists chiefly of the sole a , vamp b , two quarters, $c c$, and a button-piece, d . The quarter-lining $e e$ at the heel of the shoe is first laid together face to face and 40 stitched by a line of stitches, e' , at some distance from the edges of the quarter-pieces, and the lining is opened out flat with the main body of each quarter-lining in contact with the portion e' thereof outside the said seam, 45 and each quarter-piece is stitched to the edge e' , upon which it is so laid, by a line of stitches, as e'' , the seam e' being at such time covered

at its outside by a stay, e^4 , (see Fig. 3,) of braided or knitted fabric, which has elasticity and will stretch. In this way, when the line 55 of stitches e' is cut to enable the lining to accommodate itself to the size of the leg, the edge of the quarter-lining presents a turned or finished edge, and the elastic strip obviates leaving a hole or open space between the lining and quarter. The two quarter-pieces $c c$ are alike and extend from the sole to the top of the shoe.

The quarters are laid together face to face and stitched in usual manner from 2 to 3 to 65 form the heel seam, and above the point 3, after inturning the parallel edges of the quarter-pieces, I add a stay, f , of leather, and then lay on the said inturned edges two projecting strips, $g g$, and then I apply the gore of elastic 70 fabric h , stitching the same together by lines of stitches at 4 4. The strips $g g$ partially cover the gore, and they, together with the folded edge of the quarter-pieces c outside the stitching 4, receive the wear of the dress, keeping 75 the dress from touching and wearing the stitches 4. The strips $g g$ may be omitted, as shown in Fig. 4.

If the shoe when purchased by the one to wear it is of proper size in the leg, the seam e' 80 will not be ripped; but if too snug the difficulty may be remedied by severing the stitches e' .

I do not broadly claim a gore in a quarter, nor do I broadly claim cutting the lining to give greater freedom to the gore. 85

The lining extending to the top of the shoe back of the gore is not attached to the gore, but an open space is left between the gore and lining at 8.

The lining and quarter, except at the gore, 90 are stitched together at the top, as at 10, except inside the gore.

I have described the gore h as composed of elastic material; but the said gore might be made from leather or inelastic material in case 95 it were not desired to have the top of the shoe stretch to fit the leg, the said gore when inelastic serving as a stay and obviating the use of outside stays commonly applied outside the heel-seam or parallel thereto.

Referring to Fig. 3, I may, if desired, carry the line of stitching 4 one or more parallel rows through the lining, as shown by dotted lines, such being done when a great amount of 100

expansion is desired, and in such case the stitching e' of the lining and the stay e^t would both be cut entirely through.

I claim—

5 1. The herein-described boot or shoe, having its quarters joined together from 2 to 3 to form a short heel-seam, the edges of the quarters above the said heel-seam being inturned, and an elastic gore stitched to the said inturned 10 edges vertically above the heel-seam, all as shown and described.

2. The quarters stitched together from 2 to 3 to form a heel-seam, and the elastic gore stitched to the said quarters vertically above 15 the said heel-seam, combined with the stay f at the top of the heel-seam, substantially as described.

3. The quarters stitched together from 2 to 3 to form a heel-seam, and the elastic gore 20 stitched to the said quarters vertically above the said heel-seam, combined with the stay f at the top of the heel-seam, and with a protecting piece, g , partially overlapping the elastic gore, substantially as described.

25 4. The quarters united together from 2 to 3

to form a heel-seam, and the elastic gore stitched to the quarters above and in line with the heel-seam, combined with the quarter-lining stitched together, then opened out and stitched, each quarter-lining to a part of itself, 30 whereby when the seam uniting the two halves of the quarter is cut the edges so left will be finished or folded edges, as described.

5. The quarters united together from 2 to 3 to form a heel-seam, and the elastic gore 35 stitched to the quarters above and in line with the heel-seam, combined with the quarter-lining stitched together, then opened out and stitched, each quarter-lining to a part of itself, and with the elastic stay-strip united to the 40 quarter-lining to stretch after the seam uniting the two parts of the quarter-lining is severed, substantially as described.

In testimony whereof I have signed my name to this specification in the presence of two sub- 45 scribing witnesses.

HARRISON W. FURBER.
